3 Claims

ABSTRACT OF THE DISCLOSURE

In this electric hoist control there are utilized a lifting control pushbutton and a lowering control pushbutton mounted for depressing movement on one side of a housing, as is rather usual. With those buttons, there is an interlock cam mounted for sliding on the control housing and moved by each pushbutton during a first part of its depressing movement so as to lock the other button in neutral position. A switch is moved by the interlock cam so as to actuate a directional control circuit when the cam is moved by either button. Each pushbutton has a stem connected to a movable core of a variable transformer that forms a part of a speed control circuit. The switch having actuated a directional circuit, further depressing movement of the button will vary the current in the speed circuit.

Our invention relates to a novel pushbutton operated control that is particularly adapted for controlling speed and direction circuits on a variable speed hoist.

Those persons skilled in the art will appreciate that hoists frequently are equipped with pushbuttons that an operator will utilize to control the lifting and lowering movements of the hoist. Many people prefer a push button control because such controls are simple to operate and may very readily be connected to a hoist through a flexible cable, so as to be convenient for the operator to use while he directs his attention to a load being handled by the hoist. The novel push button control that we contribute by our invention is particularly adapted to actuate speed and direction circuits on a hoist, and will enable the operator to have extremely effective control over the movements of the hoist.

In the form of our novel control that we prefer, we utilize a pair of pushbuttons, one being a lifting control button and the other a lowering control button, each adapted to be depressed through a considerable control distance. During a first part of its depressing movement, each pushbutton will move a switch to a corresponding direction control position. Further depressing movement of the pushbutton will operate a variable current regulating device that is adapted to control a speed circuit on the hoist, but the switch will not move beyond the control position in which it was first placed by the button. Thus, as a feature of our novel pushbutton control, we utilize a switch that a pushbutton will operate to control the direction in which the hoist moves, but that will have no contacts that need slide while the pushbutton moves to operate a variable speed control device.

As a more detailed feature, we operate a direction control switch through interlocking means that will lock one of two pushbuttons in a neutral position when the other pushbutton is depressed. When further depressed, the button that is not locked will operate a variable device while the interlocking means merely hold the direction control switch in a particular operated position.

As a further feature, we prefer to utilize as a part of our novel pushbutton control, a variable current regulating device that will contribute infinite speed control while requiring no sliding contacts. That device may be a vari-

2

able transformer that is so connected to a pushbutton as to vary its current output as the button is depressed. The pushbutton first will actuate a switch that will control the direction in which the speed control is applied.

We have thus outlined rather broadly the more important features of our invention in order that the detailed description thereof that follows may be better understood, and in order that our contribution to the art may be better appreciated. There are, of course, additional features of our invention that will be described hereinafter and which will form the subject of the claims appended hereto. Those skilled in the art will appreciate that the conception on which our disclosure is based may readily be utilized as a basis for the designing of other structures for carrying out the several purposes of our invention. It is important, therefore, that the claims be regarded as including such equivalent constructions as do not depart from the spirit and scope of our invention, in order to prevent the appropriation of our invention by those skilled in the art.

In the drawing:

FIGURE 1 shows an electric hoist that is equipped with our novel pushbutton operated control.

FIGURE 2 shows a cross-section of our control, taken 25 on the line 2—2 in FIGURE 3.

FIGURE 3 is a longitudinal section showing parts of our invention.

FIGURE 4 shows diagrammatically how our control may be utilized.

Referring now more particularly to FIGURE 1 of the drawing, we show our novel pushbutton control 10 connected through a flexible cable 11 to an electric hoist 12 of a usual type. The hoist 12 has a motor 13 that will operate a drum 14 so as to wind a rope 15 on which 35 is a load hook 16, and there is a suspension hook 17 through which the hoist 12 is supported. Portions 18, 19 of the hoist housing enclose parts of the motor control circuits and the hoist mechanism, not shown. Further details of the hoist 12 are not important to an understanding of our invention, and it is merely necessary to know here that our novel pushbutton control 10 will act through wires in the flexible cable 11 to operate motor control circuits on the hoist 12.

The novel control 10 of our invention includes a pair of pushbuttons 20, 21, well shown in FIGURE 3, having stems 22, 23 that are mounted to slide in openings in a casing 24. A coil spring 25 presses each button 20, 21 in an outward direction, normally holding the button in a neutral position in which a lug 26 on each stem 22, 23 is against an inner surface of casing 24.

Referring to FIGURE 3, an interlock cam 27 is mounted for sliding movement in openings that are formed in transverse wall portions 28 on the casing 24, the cam 27 having tapered end portions 29 for coacting with surfaces on the pushbutton stems 22, 23. The cam ends 29 are so formed that each pushbutton 20, 21 will act during a first part of its depressing movement to slide interlock cam 27 in one direction or the other, causing the cam to lock the other pushbutton in neutral position. The pushbutton that slides the cam can be further depressed through a considerable distance, but when so depressed will cause no further movement of cam 27 because a side surface of the button stem will merely hold the cam in locking position.

Our control further includes a three-position switch 30, FIGURE 3, that will be operated by the interlock cam 27. As shown, switch 30 is mounted between the wall portions 28 on casing 24, and has a spring contact finger 31 engaging a recess in the cam 27. At opposed sides of contact finger 31, the switch 30 has further contact fingers 32, 33. Normally, the first contact finger 31

will be in open circuit relation to fingers 32, 33, and will act by its spring pressure to hold interlock cam 27 in neutral position. When cam 27 slides due to a depressing movement of either pushbutton 20, 21, that cam will move the contact finger 31 into circuit closing position relatively to a corresponding finger 33 or 32. It will thus be seen that interlock cam 27 upon moving to lock a pushbutton will be effective for closing a particular circuit. Also, once the cam 27 has placed switch 30 in position closing a circuit, the switch will remain in that position and will have no further movement when there is a further depressing movement of the pushbutton that has moved cam 27.

We prefer to utilize a pair of variable transformers 34, 35 that are mounted within the casing 24, as by screw studs 36 extending through openings in a wall of the casing and held by nuts 37. Each transformer 34, 35 has an axially extending core opening 38 that is in aligned relation to a corresponding pushbutton 20, 21. While not seen in FIGURE 3, each transformer 34, 35 includes a primary winding 39 and a secondary winding 40 as shown diagrammatically in FIGURE 4. On each pushbutton stem 22, 23 is a slug 41 that forms a movable core for the corresponding transformer 34, 35. The primary winding 39 of each transformer 34, 35 will be energized by a suitable source of power, and the secondary output of each transformer naturally will increase as a pushbutton moves its slug or core 41 farther into the core opening 38, as will be understood by those skilled in the art. For purposes of adjustment, each core 41 is attached to its pushbutton stem through a screw member 42 on which the core can be rotated to change its longitudinal position relatively to the stem. To facilitate that adjustment, the casing 24 is formed with openings 43 through which a tool may be inserted into engagement with a slot 43a in either core 41.

The arrangement is such that each transformer 34, 35 will produce an output that is at a minimum while the corresponding pushbutton 20, 21 is in neutral position and until that button has been depressed sufficiently to cause switch 30 to actuate a circuit. However, since transformer cores 41 can be adjusted on the screw members 42, it will be possible to set as may be desired the amount of transformer output that will be effective at the time when switch 30 closes a circuit.

We believe it will now be clear that the switch 30 of our novel control may very well be utilized for actuating alternately a lifting control circuit and a lowering control circuit for a hoist motor. Once a lifting or lowering circuit is actuated, each transformer 34, 35 may be effective for applying infinite speed control to a motor speed circuit that is responsive to a varying current. To illustrate better the manner in which our control may be used, we have shown the circuits diagrammatically in FIGURE 4. Of course, there will be a suitable source of power 44 that will energize the transformer primary windings 39. The secondary winding 40 of each transformer 34, 35 will be connected to a speed control circuit 45 for the hoist motor 13, and switch 30 will be connected to lifting and lowering control circuits 46. When the hoist operator wishes to operate the hoist in lifting direction he merely need depress the proper pushbutton, which we may assume is the button 20. As we have already indicated, a first part of the depressing movement of lifting control button 20 will slide the interlock cam 27 so as to lock the lowering control button 21 in neutral position, while also causing switch 30 to actuate lifting control circuit 46. When the operator further depresses the button 20, the speed control circuit 45 will effect operation of the hoist motor 13 in the lifting direction and at a speed corresponding to the distance through which button 20 is depressed.

Thus far we have not referred to the particular mounting of control casing 24, but it will be seen in FIGURES 2 and 3 that casing 24 may be secured through screws 50

and a bracket 51 and a plate 52, that extend about the pushbutton stems 22, 23 and the springs 25. The plate 52 may in turn be secured through screws 53, FIGURE 2, to a portion 54 of an outer housing that is indicated generally by the numeral 55. Housing portion 54 has openings for pushbuttons 20, 21, and a flexible gasket 56 extends between plate 52 and buttons 20, 21 to protect the interior of our control against the entrance of dirt. In one construction that we may use, the housing portion 54 will be secured by suitable means to a housing portion 57 that is formed with a tubular extension 58 to which the flexible control cable 11 is attached. As will be understood, the cable 11 includes a series of wires, some of which are indicated at 59, extending from the windings of transformers 34, 35 and the fingers of switch 30 to the control circuits 45, 46 and source of power 44 on the hoist 12. FIGURE 2 further shows a wire 60 supporting a strain relief bracket 61 that engages the housing portion 57.

The novel pushbutton control of our invention will enable the operator of a variable speed hoist to have extremely effective control over the operation of the hoist motor. The operator actually may apply infinite speed control, and the pushbuttons will be interlocked so that there need be no relay or other additional means to prevent conflicting operation of the control circuits. It is important to realize that our variable speed control will require no sliding electric contacts of any kind, and that it will need little or no attention for repairs after it is placed in use. While achieving these things, we are able nevertheless to make our control quite small, and it actually is possible to install our control in standard pushbutton control housings that are in use today. We believe, therefore, that the very considerable value of our novel pushbutton control will be understood, and that the merits of our invention will be fully appreciated by those persons who are skilled in the art.

We now claim:

1. In a pushbutton operated control for an electric hoist, said control having a housing, a lifting control pushbutton and a lowering control pushbutton individually mounted for depressing movement relatively to a particular side of the housing, each pushbutton having a stem moving in a linear direction in the housing when the button is depressed from a neutral position, the improvement that comprises interlocking means moved by each pushbutton stem during a first part of the depressing movement of its button whereby to lock the opposed button in neutral position, in combination with a plurality of electric current regulating devices each operable for effecting a varying current control, each of the pushbutton stems being connected to a separate one of said current regulating devices so as to operate that device while the corresponding pushbutton is depressed varying distances, a switch having contacts normally in a neutral position and movable to an actuated position, and a portion of said interlocking means coacting with said switch to move its contacts to actuated position when said interlocking means move to lock a pushbutton.

2. A construction as set forth in claim 1, in which each current regulating device is a variable transformer mounted on said housing and having a core connected to a pushbutton stem so as to be moved by a pushbutton for varying the output of said transformer.

3. A construction as set forth in claim 1 in which said interlocking means include an interlock cam mounted to slide in a transverse direction on the housing, a surface on one pushbutton stem coacting with an end of said cam for sliding said cam, and said switch including a series of contact fingers one of which engages said cam, so that said cam will move said one contact finger alternately into contact with each of two other fingers when alternate pushbuttons are depressed.
